Patented Feb. 12, 1918.

By Watson E. Coleman

Attorney

UNITED STATES PATENT OFFICE.

FRANK FESSLER, OF WOODBRIDGE, NEW JERSEY.

WRENCH.

1,256,216.

Specification of Letters Patent. Patented Feb. 12, 1918.

Application filed December 19, 1917. Serial No. 207,908.

To all whom it may concern:

Be it known that I, FRANK FESSLER, a citizen of the United States, residing at Woodbridge, in the county of Middlesex 5 and State of New Jersey, have invented certain new and useful Improvements in Wrenches, of which the following is a specification, reference being had to the accompanying drawings.

- 10 This invention relates to certain improvements in wrenches and has relation more particularly to a device of this general character of a rigid jaw type and it is an object of the invention to provide a wrench of this 15 general character with novel and improved means whereby the jaws may be readily and conveniently applied or removed so that the wrench may be employed with work of different sizes.
- 20 It is also an object of the invention to provide a device of this general character having novel and improved means whereby a rigid jaw may be securely maintained in applied position upon a handle or shank and 25 whereby the same can be removed with facility when the occasion of practice requires.

The invention consists in the details of construction and in the combination and arrangement of the several parts of my improved wrench whereby certain important advantages are attained and the device rendered simpler, less expensive and otherwise more convenient and advantageous for 35 use, as will be hereinafter more fully set forth.

The novel features of my invention will hereinafter be definitely claimed.

In order that my invention may be the 40 better understood, I will now proceed to describe the same with reference to the accompanying drawings, wherein:

Figure 1 is a view in side elevation with a portion broken away of a wrench constructed in accordance with an embodiment 45 of my invention;

Fig. 2 is a view in top elevation of my improved wrench as herein embodied with one end portion in section; and

50 Fig. 3 is a view in elevation of a series of jaws as herein employed and which are adapted to be interchanged.

As disclosed in the accompanying drawings 55 1 denotes a handle or shank substantially S-shape or sigmoidal in form and which has each of its opposite ends inbowed

as at 2 and the transverse center of said inbowed end 2 is provided with a recess or channel 3 extending substantially entirely therealong. The opposite faces of the handle or shank 1 at each end portion thereof are provided with the elongated and longitudinally disposed recesses 4 having their outer ends flared and open at the outer end thereof. Bridging each of the recesses 4 at 60 a predetermined point inwardly of its inner end is a cross member 5 which is preferably flush with the adjacent side face of the handle or shank 1 and spaced from the bottom of the recess 4.

J denotes a rigid jaw of a conventional type having the inner portion 6 thereof outbowed as particularly illustrated in Fig. 1 and adapted to snugly fit within the inbowed end portion 2 of the handle or shank 70 1 and said outbowed portion 6 at the transverse center thereof is provided with the outstanding rib or flange 7 adapted to snugly fit within the groove or channel 3 hereinbefore referred to. The side faces of 80 the jaw J at the transverse center thereof are provided with the rearwardly directed spring or resilient arms 8 adapted to snugly fit within the recesses 4. Each arm 8 is provided in its outer face with a transverse groove or slot 9 to receive a cross 85 member 5 whereby the jaw J may be effectively locked in applied position upon the handle or shank 1. As is particularly illustrated in the accompanying drawings each 90 of the arms 8 extends beneath a cross piece 5 and the coating recess 4 is of such a depth as to permit the arm 8 to be forced inwardly a distance sufficient to permit the disengagement of the arm 3 from the cross 95 piece 5 when it is desired to remove the jaw J.

The opposite ends of the outbowed portion 6 of the jaw J is defined by the shoulders 10 having their opposed faces in diverging relation and which are adapted to overlie or contact with corresponding faces 11 at the opposite ends of the inbowed portion 2 whereby the strain imposed upon the jaw J during the working operation is imparted directly upon the handle or shank 1 and the 100 spring arms 8 relieved therefrom.

In practice it is intended that with each handle or shank 1 a plurality of jaws J are adapted to be employed, said jaws being of 110 different sizes to compensate for different sizes of work and in view of the foregoing

- description it is thought to be self-evident that the jaws J may be readily and conveniently interchanged when the requirements of practice may necessitate. It is also preferred that the handle or shank 1 be gradually decreased in thickness from one end toward the other as indicated in Fig. 2 so that the jaw J mounted upon one end of the handle or shank 1 may be employed in connection with smaller work than the jaw at the opposite end of the handle or shank 1.
- From the foregoing description, it is thought to be obvious that a wrench constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.
- 20 I claim:
1. A wrench comprising a shank having open recesses in opposite faces thereof, a cross-piece bridging each of said recesses intermediate the length thereof, a jaw, and spaced spring arms extending from the jaw and seatable within the recesses of the shank, said arms being provided with shoulders to
- 25 contact with the inner edges of the cross-piece.
2. A wrench comprising a shank having open recesses in opposite faces thereof, a cross-piece bridging each of said recesses intermediate the length thereof, a jaw, and spaced spring arms extending from the jaw

and seatable within the recesses of the shank, said arms being provided with shoulders to contact with the inner edges of the cross piece, the opposed faces of the jaw and shank, when the jaw is in applied position, being provided with an interlocking rib and groove.

3. A wrench comprising a shank having open recesses in opposite faces thereof, a cross-piece bridging each of said recesses intermediate the length thereof, a jaw, and spaced spring arms extending from the jaw and seatable within the recesses of the shank, said arms being provided with shoulders to contact with the inner edges of the cross piece, said jaw at opposite sides of the arms being provided with inwardly directed shoulders overlying adjacent faces of the shank.

4. A wrench comprising a shank having open recesses in opposite faces thereof, a cross piece bridging each of said recesses intermediate the length thereof, a jaw, and spaced spring arms extending from the jaw and seatable within the recesses of the shank, said arms being provided with shoulders to contact with the inner edges of the cross piece, the opposed faces of the jaw and shank, when the jaw is in applied position, being provided with an interlocking rib and groove, said jaw at opposite sides of the arms being provided with inwardly directed shoulders overlying adjacent faces of the shank.

In testimony whereof I hereunto affix my signature in the presence of two witnesses.

FRANK FESSLER.

Witnesses:

GERTRUDE LEWIS,
W. E. LAWSON.
